APPARATUS AND METHOD FOR BENDING
AND STRAIGHTENING CURVED PRINTING
PLATES AND THE LIKE

Joseph Schwartz, Melrose Park, Pa., and Amos Ackley, Camden, N. J., assignors to Westcott & Thomson, Inc., Philadelphia, Pa., a corporation of Pennsylvania

Application May 23, 1952, Serial No. 289,511

4 Claims. (Cl. 153—32)

1.

This invention relates to an apparatus and method for modifying the shape of a curved plate, and more specifically relates to apparatus and method for holding a curved printing plate and carrying out surface shaping and restoring operations thereon.

Curved printing plates are used extensively in connection with automatic printing machines which embody a cylinder or other rounded member to which the curved printing plate may be attached. The etched or printing surface of the curved plate faces outwardly and is adapted automatically to contact the successive sheets of paper upon which the printed matter is to be impressed. For proper automatic operation of the machine, and particularly for uniform and accurate reproduction of the printed matter, it is essential that the printing face of the printing plate be absolutely uniform; that is, the surface must be uniformly curved and free of "high" spots or "low" spots which will tend either to print too boldly or too lightly in local portions of the total printed area.

In the course of preparation of such printing plates, they are frequently handled or processed in such manner that low spots tend to develop on the printed surface, and it is accordingly one object of this invention to provide economical, rapid and accurate method and means for eliminating localized low spots from a curved printing plate. Other objects and advantages of the invention, including the simplicity and economy of the same, the accuracy and speed with which it may be practiced, and the ease of adjustability of the device for accommodation of work objects of different sizes and diameters, will appear in further detail hereinafter and in the drawings, whereof:

Fig. 1 is a perspective view of the apparatus comprising one embodiment of the invention, showing, in full line, a movable clamp element in inoperative position withdrawn from the work;

Fig. 2 is an enlarged fragmentary sectional view taken as indicated by the lines and arrows II—II which appear in Fig. 1;

Fig. 3 is an enlarged fragmentary sectional view taken as indicated by the lines and arrows III—III which appear in Fig. 1, with parts broken away, and shown in section in order more clearly to disclose important details;

Fig. 4 is a sectional view taken as indicated by the lines and arrows IV—IV in Fig. 1, showing the clamp element in operative position relative to the work;

Figs. 5, 6 and 7 show one procedure for flatten-

ing one face of the work; and the product obtained in accordance with such procedure; and Figs. 8, 9 and 10 show, in steps corresponding to those in Figs. 5, 6 and 7 respectively, one procedure in accordance with this invention, and the product attained in accordance with such procedure.

In the following detailed description which relates to one specific embodiment of this invention as shown in the drawings, specific terms will be employed for the sake of clarity, but it is to be understood that such terms are used in a descriptive sense and are not intended to limit the scope of the invention.

Referring to the drawings, the device there shown includes a concave slab 11 having a concave upper face 12 the shape of which conforms substantially to the shape of the lower face of a work object 13, here illustrated as a printing plate which may consist of relatively soft, malleable metal. The face 12 of concave slab 11 and the face of the work object 13 both have the shape of a portion of a cylinder. However, due to non-uniformity of the work objects 13, they do not necessarily fit snugly against the concave upper face 12 of concave slab 11.

Fixed to one end of concave slab 11, at opposite sides thereof, are a pair of curved ratchet bars 14 which extend upwardly beyond the end of concave slab 11. The curved upper surface of each ratchet bar 14 is flush with the concave upper face 12. Transverse brace rods 15 serve to maintain the parallel relationship of ratchet bars 14. Slidably mounted on each ratchet bar 14 is a rider carriage 16 which has upper flanges 17 in contact with the upper surface of the ratchet bar 14. A cross bar 20 is affixed to, and bridges the space between, the rider carriages 16. The bottom face of cross bar 20 has the same curvature as the top faces of the ratchet bars 14. Cross bar 20 has capacity to be swung inwardly and outwardly through the arc defined by the curvature of the ratchet bars 14, and to move immediately adjacent the upper face 12 of concave slab 11 to an operative position against an end of work object 13, as indicated in dot-dash lines in Fig. 1.

The rider carriage 16, see particularly Fig. 2 of the drawings, includes side wall 21 which sustains a transverse pivot pin 22. Rotatably mounted on the pivot pin 22 is a pawl 23 engageable with the ratchet bar 14. The pawl 23 includes a handle 24, and is spring urged against the ratchet bar 14 by means of a spring 25. The pawl 23 also has a slot at 26 through which the

headed screw 27 slidably extends. Screw 27 is fixed in side wall 21 and serves to retain the pawl 23 against the side wall 21 and as a limit stop for the rotary movement of the pawl 23 around pivot pin 22.

Fixed to the opposite end of concave slab 11, opposite the rider carriages 16, are three screw clamp elements comprehensively designated by the number 30. Referring particularly to Fig. 3 of the drawings, a rigid base 31 is affixed to to the end of the concave slab 11 and provided with threaded apertures for reception of the threaded shafts 32. The upper side of rigid base 31 is flush with the upper face 12 of concave slab 11. Each threaded shaft 32 extends through an aperture in the base of a channel iron 33 having a lower wing 34 and an upper wing 35 longer than lower wing 34. The upper wing 35 normally extends beyond the fixed base 31 and contacts the upper face 12 of concave slab 11. The end of upper wing 35 is constructed and arranged to contact the adjacent end of work object 13. Fixed to the threaded shaft 32 is a head 36 with handle members 37, whereby the threaded shaft 32 may be rotated manually to clamp the work object 13 in place. A coil spring 40, normally under compression, is fitted at one end under the head 36 and at the other end in a recess at the base of channel iron 33.

In operation, the presence and location of low spots on printing plates is determined by rubbing a flat piece of chalk or the like on the bottom face of the printing plate, which is the etched or printing face of the plate. The chalk adheres substantially uniformly to the true portions of this face, but no chalk rubs off on the printing face portion of the low spot. The opposite face of the printing plate may then be marked to show the locations of all low spots found.

The work object 13 thus marked is placed, with the marked side up, on the concave slab 11 with one end substantially in contact with the upper wings 35 of screw clamp elements 30. The rider carriages 16 together with cross bar 20 are then swung downwardly and inwardly toward the work object 13, along the ratchet bars 14 which serve as tracks, to the position shown in dot-dash lines in Fig. 1. The pawls 23 and ratchet bars 14 coact to maintain the inner edge of cross bar 20 against the adjacent end of work object 13. The work object 13 is thereby maintained between the clamp elements adjacent its opposite ends, with relatively light pressure exerted on said ends. The operator now turns the threaded shafts 32, forcing the upper wings 35 under relatively great pressure against the work object, the pressure being resisted by the pawls 23 and ratchet bars 14 at the opposite end of the work object 13. The opposed forces A thus applied to the opposite ends of the concave work object 13 have downwardly directed components B which expand the work object 13 under pressure against the upper face 12 of concave slab 11, as indicated in Fig. 4 of the drawings. Thus the work object 13 is in uniform intimate contact throughout its length with the concave slab 11.

The work object, held under pressure in this manner, is preferably processed as indicated in Figs. 8-10 of the drawings, wherein the operator hammers downwardly upon the low spots 41, which do not contact the upper face 12 of concave slab 11. It will be appreciated that the

portion 41 is shown greatly enlarged in the drawings.

After concluding the hammering operation, the screw clamp elements 30 are loosened or the pawl handles 24 manipulated permitting the removal of the uniformly curved printing plate which is free of low spots, as shown in Fig. 10, from the concave slab 11.

We have found that it is of vital importance to force the printing plate under relatively high pressure against the concave slab, in order to attain proper results. Referring to Figs. 5-7, the printing plate 13' is not urged against the concave slab 11' with sufficient force to maintain the opposed surfaces in intimate contact with one another; the printing plate "bridges across" the concave slab. Accordingly a hammer blow, directed against the low spot 41' of Fig. 5, often fails to correct the shape of the work spot and, on the contrary, produces a "high spot" 42, see Fig. 6, since the momentum of the hammer is not opposed by the concave slab 11' at the precise point where the hammer is applied to the printing plate. A high spot of the character thus produced cannot properly be repaired by hammering on the opposite, or lower face of the printing plate since the etching or print which appears on this lower face is readily distorted or obliterated by hammering directly thereon. A plate as shown in Fig. 7, having a high spot 42, does not perform properly in an automatic printing press and produces a non-uniform printed product.

Not only does our apparatus eliminate the formation of high spots as indicated in Figs. 5-7, but it provides rapid and efficient preliminary means for clamping a printing plate or like work object in appropriate position, coacting with final clamping means for exerting a high pressure on the work object, whereby extremely accurate and rapid processing may be realized.

It will be appreciated that, although the invention has been described in detail with reference to one embodiment thereof, it may also be practiced by substituting a wide variety of modifications or equivalents for the elements shown and described herein. All such modifications, including reversals of parts and the use of certain features independently of the use of other features, are within the spirit and scope of the invention as defined in the appended claims.

Having thus described our invention, we claim:

1. Apparatus for bending and straightening a curved plate or the like, comprising a concave slab adapted to support said plate, readily adjustable clamping means manually swingable to a position above and adjacent said concave slab against one end of said plate, screw clamp means fixed on said concave slab effective upon the other end of said plate, and means to operate said screw clamp and thereby apply force to said other end of said plate, whereby the opposite ends of said plate are compressed toward one another and the body of said plate is expanded for intimate contact under pressure with said concave slab.

2. Apparatus for modifying the surface shape of a concave plate comprising a concave slab having a fixed curvature substantially similar to the initial curvature of said concave plate, tracks at one end of said concave slab, a carriage mounted for movement along each of said tracks, a ratchet member on each of said tracks, a pawl element on each of said carriages and coacting with said ratchet member, a cross piece spanning said tracks and affixed to said carriages, said carriages

and cross piece being movable along said tracks as a unit with the cross piece immediately adjacent the curved face of said concave slab, whereby said cross piece is adapted to abut the edge of one end of said concave plate, and a plurality of screw clamps mounted on the other end of said concave slab, said screw clamps including clamping elements adapted to extend immediately adjacent the surface of said concave slab to abut against the edge of the other end of said concave plate.

3. An apparatus for holding a curved plate comprising a concave slab of determined curvature, adjustable clamping means fixed to one edge of said slab, substantially parallel tracks having a curvature substantially equal to that of said slab, said tracks being fixed to and extending beyond the opposite edge of said slab, and separate clamping means slidably supported on and spanning said tracks.

4. In a method of straightening a localized low spot on the printing surface of a curved printing plate, the steps comprising placing said curved printing plate on a concave slab with the printing surface disposed adjacent said slab, said slab 25

having a curvature in excess of the curvature of the plate whereby the plate bridges across the slab, compressing opposed ends of said plate toward one another thereby expanding said printing surface with the exception of said low spot against said concave slab, deforming the face of said plate locally in the area of said low spot toward said concave slab to bring the printed surface at said low spot in uniform contact with the adjacent portion of said slab, and continuously maintaining the compression of the opposed plate ends toward one another during the deformation step.
